UNITED STATES PATENT OFFICE.

EDWIN M. ROSENBLUTH, OF PHILADELPHIA, PENNSYLVANIA.

ACETYLENE-GAS GENERATOR.

1,079,665.

Specification of Letters Patent.

Patented Nov. 25, 1913.

Application filed October 4, 1909. Serial No. 520,943.

To all whom it may concern:

Be it known that I, EDWIN M. ROSENBLUTH, of Philadelphia, in the county of Philadelphia and State of Pennsylvania, have invented a certain new and useful Improvement in Acetylene-Gas Generators, whereof the following is a specification, reference being had to the accompanying drawings.

10 As hereinafter described, my invention includes a generator having a jacket forming a vacuum chamber surrounding its water receptacle and rendering the latter capable of maintaining water at the uniform temperature best adapted for the production of gas, regardless of exposure of the generator to extremes of temperature. Such an arrangement is advantageous in that it prevents freezing of the water in 15 winter weather and over-heating of the water when the generator is exposed to torrid sunlight.

Although I have shown my invention embodied in a generator of the type described 25 in Letters Patent of the United States No. 903,507 granted to me November 10, 1908, it is to be understood that my improvement may be applied to generators of other types.

30 My invention includes the various novel features of construction and arrangement hereinafter more definitely specified.

Certain of the features of construction herein set forth, including the means connecting the base frame and water receptacle through the carbid casing, and the detachable condensing coil carried by a foraminous casing, are claimed in my copending application Serial No. 508,369, filed July 19, 1909 35 for Letters Patent of the United States 1,025,648 dated May 7, 1912.

In said drawings:—Figure I, is a vertical sectional view of said generator taken on the line I, I, in Fig. II. Fig. II, is a plan view of said generator. Fig. III, is a plan view of the generator base and condenser. Fig. IV, is a fragmentary sectional view taken on the line IV, IV, in Fig. II. Fig. V, is a fragmentary sectional view 40 taken on the line V, in Fig. I. Fig. VI, is a fragmentary sectional view taken on the line VI, in Fig. I. Fig. VII, is a fragmentary sectional view similar to Fig. VI, but showing the valve in different position. Fig. 45 VIII, is a fragmentary sectional view taken on the line VIII in Fig. I, showing the air

valve in the position corresponding with Fig. V. Fig. IX, is a fragmentary sectional view similar to Fig. VIII but showing said air valve in the position corresponding with Fig. VII. Fig. X, is a plan view of a modified form of a generator base and condenser. Fig. XI, is a fragmentary vertical sectional view of said base and condenser taken on the line XI, XI, in Fig. X.

In said drawings, the base frame 1 is arranged to be permanently attached by screws 2 to any convenient supporting means 3, for instance, the running board of an automobile, and is arranged to support the carbid casing 4 and water receptacle 5 in separable relation. Said carbid casing has the central tube 6 and the concentric annular flange 7 in rigid relation with its bottom wall 8, and fitted to the central vertical stem 9 on said base frame 1. Said stem is screw threaded at its upper end for engagement with the rotary connecting rod 11 which depends through the central tube 12 of the water receptacle 5, in concentric relation with the annular flange 13 upon the top frame 14 of said receptacle. The upper flange 15 of said casing 4, fits between the flanges 16 and 17 carried by said water receptacle 5 and holding the gasket 18 between them for engagement with said flange 15, and, the arrangement described is such that when said carbid casing 4 is set upon the gasket 20 which is attached to the base 1 by the flange 21, and, said water receptacle 5 is fitted to said carbid casing and both separably connected with said base 1 by the engagement of said rod 11 and stem 9, as shown in Fig. I; the annular flanges 7, 13 and 15 are embedded in the respective gaskets 18, 20 and 22, and a closed gas chamber 23 is formed between said casing and receptacle. The gas which accumulates in said chamber to which it may rise by way of the interstices between the carbid casing 4, the basket 38 and the dome 41, or through the central tube 6 is normally discharged through the space around the rod 9 in the tube 6, apertures 24 and passageway 25 in the tubular lower end of said stem 9 to the liquid trap 26 in said base 1, and thence through the branch 27 to the condensing coil 29 from which the gas is conveyed to the lamps, conveniently by a flexible tube. Said base 1 is provided with the vertical tubular standard 32 extending in rigid connection therewith through said coil 29 and support-

ing the latter, and, as indicated in Fig. I said standard is open at both ends to the atmosphere, being provided at its lower end with the air inlets 33. The condensate 34 from the gas thus cooled in said coil 29 flows into said trap 26 which has the opposite end screw caps 35 and 36 so that it may be readily emptied and cleaned. The passage 25 may also be readily cleaned when the plug 37 is removed. As shown in Fig. I, said carbid casing 4 incloses the removable basket 38 having the foraminous bottom wall 39 supporting the carbid 40. The flange at the top of said basket 38, rests 15 loosely upon the ledge of said casing 4 so as to permit the passage of gas thereat. The dome 41 separably fitted in said basket 38, supported at the height indicated by the brackets 42 in said basket, and held by its 20 spring 43, serves to distribute circumferentially in said basket, the water which drips thereon through the water outlet 44 in the bottom of said water receptacle 5. Said water flowing down said dome first 25 reaches the carbid at the lower edge of said dome immediately below the water port 44, and, being distributed in the space between said dome and basket contacts with the carbid throughout the circumference of the 30 lower edge of the dome. The bead 46 formed in said dome above its lower edge as shown in Fig. I, merely serves to stiffen the same and is not essential to the afore- 35 said circumferential distribution of said water. As indicated said water outlet is restricted by the loose reciprocatory plunger 45 which rests upon said dome. Said water receptacle 5, has the jacket 47 maintained in spaced relation therewith as indicated in 40 Fig. I forming a vacuum chamber 48 surrounding said receptacle, said chamber being provided with the air vent tube 50 sealed at its inner free end 51, through which the air is primarily exhausted from said chamber 48. The passage of water 52 from said receptacle to said carbid casing is controlled by the rotary valve 53 provided with 45 said outlet 44 and carrying said plunger 45. Said valve is mounted in the casing 50 54 rigidly secured to the bottom wall 55 of said receptacle and having the ports 57 and 58 which when said valve is turned to the position shown in Figs. I, II, and VI register with the ports 60 and 61 in said 55 valve 53, permitting the passage of water from said receptacle to the carbid casing. However, when said valve 53 is turned to the position shown in Fig. VII, said ports 57 and 58 in the valve casing are closed to 60 prevent the further discharge of water to the carbid casing, and, contemporaneously the gas port 62 in said valve registers with the gas port 63 in said valve casing 54 which opens into the gas chamber 23 through the base of said casing and leads

to the hollow stem 64, having the handle 65, by which said valve 53 is rotated. As shown in Fig. I, said stem 64 is open at its upper end to the atmosphere, so that when said valve 53 is turned to permit the water 70 52 to drip into the carbid casing, the escape of gas through said valve 53 and stem 64 is prevented, but when said valve 53 is turned to shut off the water, after generated gas is permitted to escape to the atmosphere through said valve and stem. In order to permit the regulated flow of water from said water receptacle 5 to the carbid casing when said valve 53 is opened, as above described, it is necessary that the space 66 in 75 said receptacle above the water 52 shall be in communication with the atmosphere and therefore I provide the tube 67 which extends through the upper wall of said receptacle 5 vacuum chamber 48 and its jacket 47 80 and has the airport 69 above the latter controlled by the annular valve 70 which is carried by said handle 65 on said stem 64 in rigid relation with said valve 53 at the lower end thereof. Said air valve 70 has the port 71 which as shown in Fig. VIII registers with said port 69 when said valve 53 is in the position shown in Fig. VI, so that air is admitted to said receptacle 5 when the water 52 is permitted to drip therefrom, but when said valve 53 is turned to the position indicated in Figs. VII and 90 IX, said air port 69 is closed by said valve 70. 95

The inlet by which the water is supplied to said receptacle includes the tube 72 which as shown in Fig. IV extends through the upper wall of the receptacle 5, the vacuum chamber 48 and the jacket 47 in hermetically sealed relation therewith and is provided with the tubular bearing 73 through which the rod 74 may be reciprocated and rotated. Said rod 74 is rigidly connected with the cap or closure 75 having the gasket 76 fitted to the upper end of said tube 72, and the lower end of said rod is provided with a spring 78 by which said closure is normally held down in air tight relation with said tube. It is to be understood that said closure may be lifted against the tension of 100 said spring 78 and turned to the position indicated in dotted lines in Figs. II and IV, whenever it is desired to use said tube 72 as a water inlet or outlet. The advantage of 105 said arrangement is that said closure cannot be lost or mislaid and when turned to register with said inlet tube 72, automatically seals it. 110

Although I find it convenient to mount the tubular standard 32 on said base 1, in 115 eccentric relation with the stem 9, so that said base may be permanently secured upon its support 3, in a position where said coil 29 is protected from being crushed; a condensing coil may be supported upon a tubu- 120 130

lar standard carried by the base frame in concentric relation with the stem upon the latter, as in the form of my invention shown in Figs. X and XI, wherein the base frame 5 81 is arranged to support the carbid casing 84 and water receptacle 85 in separable relation and has the central stem 87, similar to the stem 9 above described, having the apertures 88 and the passageway 89 through 10 which the gas is discharged into the liquid trap 90. Said trap 90 has the removable plug 91 affording access to said passage 89, and, the removable end cap 92, permitting the discharge of the condensate. The gas is 15 discharged from said trap 90 through the branch 94 connected with the condensing coil 95, supported by the tubular standard 96 extending vertically in rigid relation with said base frame 81 and open to the atmosphere 20 at the top and bottom. I find it convenient to provide said coil 95 with the foraminous cover 98 which is removably supported by said tubular standard 96, said cover having the opening 99 through which 25 the upper end of said coil 95 projects, as indicated in Fig. X, for engagement with a flexible tube or other conduit leading to the lamps. As said condensing coil 95 surrounds the carbid casing 84 and may be 30 heated above the atmospheric temperature by the generation of gas in said casing, I find it convenient to provide said tubular standard 96 with a layer of material 100 which is a nonconductor of heat, for instance 35 asbestos fabric, interposed between said coil and standard and held on the latter by the strips 101.

It may be observed that in both forms 40 of my invention above described, the base frame is provided with a tubular stem by which the carbid casing and water receptacle are separably retained in rigid relation therewith, and the condensing coil is supported by said base independently of said 45 carbid casing and water receptacle, with the advantage that the flexible tube or other conduit through which the gas is discharged from said coil need not be disconnected or disturbed when it is desired to remove or 50 separate said carbid casing and water receptacle. Although said coils 29 and 95 are normally retained in rigid relation with their respective base frames, they are detachably connected with the respective 55 branches 27 and 94, by union fittings, as shown, so that said coils may be readily removed and replaced.

I do not desire to limit myself to the precise details of construction and arrangement 60 above described, as it is obvious that various modifications may be made therein without departing from the essential features of my invention as defined in the appended claims.

I claim:—

65 1. In an acetylene gas generator, the

combination with a water receptacle surrounded by a vacuum jacket, having a water inlet including a tube extending through said jacket and the wall of said water receptacle; of a removable closure for said tube; and, a spring pressed rod forming a pivot for said closure and normally retaining the same in closed position. 70

2. In an acetylene gas generator, the combination with a water receptacle surrounded by a vacuum jacket, having a water inlet including a tube extending through said jacket and the wall of said water receptacle; of a removable closure for said tube; and, a spring normally retaining the same in closed 75 position. 80

3. In an acetylene gas generator, the combination with a base frame arranged to be permanently secured to supporting means; of a stem extending upwardly from said base frame and having a threaded upper end; a carbid casing having a tube extending centrally through it and surrounding said stem; a water receptacle detachably fitted upon said carbid casing and forming 85 a gas chamber; a tube in said receptacle forming a central passageway therethrough; a connecting rod extending through said passageway in engagement with said stem; and, a jacket on said receptacle forming a 90 vacuum chamber surrounding the same. 95

4. In an acetylene gas generator, the combination with a carbid receptacle; of a water receptacle detachably fitted upon said carbid receptacle and forming a gas chamber; a 100 base frame arranged to be permanently secured to supporting means; a rod extending through said water receptacle and carbid casing in connection with said base frame; and, a condensing coil carried by said base 105 frame, independently of said water receptacle and carbid casing but in communication with said gas chamber.

5. In an acetylene gas generator, the combination with a carbid receptacle; of a water 110 receptacle detachably fitted upon said carbid receptacle and forming a gas chamber; a base frame arranged to be permanently secured to a convenient supporting means; a rod extending through said water receptacle 115 and carbid casing in connection with said base frame; and, a condensing coil carried by said base frame in concentric relation with said rod, independently of said water receptacle and carbid casing but in communication 120 with said gas chamber.

6. In an acetylene gas generator, the combination with a base frame arranged to be permanently secured to supporting means; of a carbid casing having a tube extending 125 through it; a water receptacle detachably fitted upon said carbid casing and forming a gas chamber; a tube in said receptacle forming a central passageway therethrough; a connecting rod extending through said tubes 130

in engagement with said base; and, a jacket on said receptacle forming a vacuum chamber surrounding the same.

7. In an acetylene gas generator, the combination with a carbid casing; of a separable water receptacle; a jacket carried by said water receptacle forming a vacuum chamber surrounding the same; a base frame, and a connecting rod extending through said jacket, said water receptacle and carbid casing in detachable connection with said base frame.

8. In an acetylene gas generator, the combination with a carbid receptacle and a detachable water receptacle; of a jacket for said water receptacle forming a vacuum chamber surrounding the same; and, an air vent tube extending into said water receptacle from said vacuum chamber and having its free end sealed.

9. In an acetylene gas generator, the combination with a carbid receptacle and a water receptacle; of a jacket for said water receptacle forming a vacuum chamber surrounding the same; and, a sealed air vent for said chamber in the wall of said water receptacle.

10. In an acetylene gas generator, the combination with a carbid receptacle and a detachable water receptacle; of a jacket for said water receptacle forming a vacuum chamber surrounding the same; an air port leading from said water receptacle to the atmosphere; and, a rotary valve controlling said air port, operatively connected with a valve controlling a water passageway leading from said water receptacle into said carbid casing and also controlling a gas passageway leading from said carbid casing to the atmosphere through a hollow stem connecting said valves.

11. In an acetylene gas generator, the combination with a carbid casing; of a water receptacle fitted thereto in separable gas tight relation, forming a gas chamber; a base frame; means detachably connecting said carbid casing and water receptacle with said base frame; and a condensing coil carried by said base frame independently of said water receptacle and carbid casing but in communication with said gas chamber; said base frame being provided with a liquid trap between said gas chamber and condensing coil and in communication therewith, and having a tubular standard extending vertically within said coil, supporting the latter and open to the atmosphere at the top and bottom of said coil.

12. In an acetylene gas generator, the combination with a carbid casing; of a water receptacle fitted thereto in separable gas tight relation, forming a gas chamber; a base frame; means detachably connecting

said carbid casing and water receptacle with said base frame; and a condensing coil carried by said base frame independently of said water receptacle and carbid casing but in communication with said gas chamber; said base frame having a tubular standard extending vertically within said coil, supporting the latter and open to the atmosphere at the top and bottom of said coil.

13. In an acetylene gas generator, the combination with a carbid casing; of a water receptacle fitted thereto in separable gas tight relation, forming a gas chamber; a base frame; and means detachably connecting said carbid casing and water receptacle with said base frame, including a central tubular stem on said base frame, forming a gas conduit.

14. In an acetylene gas generator, the combination with a carbid casing; of a water receptacle fitted thereto in separable gas tight relation, forming a gas chamber; a base frame; and means detachably connecting said carbid casing and water receptacle with said base frame, including a tubular stem on said base frame, forming a gas conduit.

15. In an acetylene gas generator, the combination with a base frame arranged to be permanently secured to supporting means; of a carbid casing removably supported by said base frame; means detachably connecting said carbid casing with said base frame; a condensing coil carried by said base frame, having its lower end in communication with the bottom of said carbid casing.

16. In an acetylene gas generator, the combination with a carbid receptacle and water receptacle; of a valve controlling the flow of water from said receptacle; means forming a vacuum chamber surrounding said water receptacle; means, extending through said vacuum chamber, whereby said valve may be operated; and a sealed air vent for said chamber so located as to be inaccessible from the exterior of said chamber.

17. In an acetylene gas generator, the combination with a water receptacle; of a valve controlling the flow of water from said receptacle; means forming a vacuum chamber surrounding said receptacle; means extending through said vacuum chamber, whereby said valve may be operated; and a sealed air vent for said chamber.

In testimony whereof I have hereunto signed my name at Philadelphia, Pennsylvania, this thirtieth day of September, 1909.

EDWIN M. ROSENBLUTH.
